Des. 204,032
Patented Mar. 8, 1966

204,032

SLIDE PROJECTOR

Walter Herbst, Evanston, and Ralph M. La Zar, Skokie, Ill., assignors to Sawyer's, Inc., Portland, Oreg., a corporation of Oregon

Filed Apr. 29, 1965, Ser. No. 85,026

Term of patent 14 years

(Cl. D61—1)

FIG. 3.

FIG. 5.

FIG. 1 is a front perspective view of a slide projector showing our new design, the handle thereof raised to its carrying position;

FIG. 2 is a similar view but showing the handle lowered and tilted forward;

FIG. 3 is a right-side elevational view thereof, with the handle lowered but vertically oriented as for storage of the projector;

FIG. 4 is a left-side elevational view thereof;

FIG. 5 is a front elevational view thereof;

FIG. 6 is a rear elevational view thereof;

FIG. 7 is a top plan view thereof; and

FIG. 8 is a bottom plan view thereof.

We claim:

The ornamental design for a slide projector, substantially as shown.
